PRESS ROLL ASSEMBLY

Lloyd Hornbostel, Beloit, Wis., assignor to Beloit
Iron Works, Beloit, Wis., a corporation of
Wisconsin

Application May 5, 1945, Serial No. 592,236

2 Claims. (Cl. 92—49)

1

This invention relates to a press roll assembly and more particularly to a fluid pressure controlled horizontal press roll assembly for use in machines for making paper and similar fibrous web material.

It has heretofore been customary in press roll assemblies for paper machines to effect the pressure contact between the rolls by the use of screw mechanisms acting through compression springs. It is difficult, however, by the use of such mechanisms to insure the proper amount of pressure between the rolls or to gauge the amount of pressure that is being exerted, so that not infrequently unequal pressures obtain at different points along the lines of contact between the rolls.

In accordance with my present invention, the amount of pressure between the surfaces of co-operating press rolls is readily controlled through the medium of fluid pressure actuated mechanism, such as diaphragms. Means are provided for controlling the amount of fluid pressure acting upon the diaphragms and thus for accurately controlling the degree of pressure between the contacting surfaces of the press rolls. Pressure indicating gauges serve to indicate the amount of fluid pressure exerted against the diaphragms, whereby any desired amount of pressure can be set up and maintained during the operation of the press assembly. In this way, unequal pressure at the ends of the press rolls can be avoided, with the result that a more uniform and efficient operation of the press roll assembly in the removal of water from paper webs and the like can be realized.

It is therefore an important object of this invention to provide a press roll assembly in which fluid pressure actuated means are utilized for effecting and maintaining the desired amount of pressure between the contacting surfaces of the rolls.

It is a further important object of this invention to provide a fluid pressure controlled horizontal press assembly in which the middle roll is stationarily mounted and the outer rolls are pivotally mounted, and in which fluid pressure actuated means are employed for determining and maintaining the proper degree of pressure between the several rolls.

Other and further important objects of this invention will be apparent from the disclosures in the specification and the accompanying drawings.

On the drawings:

Figure 1 is an end elevational view, partly 55 facing each other. Pins 26, 26 are normally re-

2

broken away and in section, illustrating a horizontal press roll assembly of my invention.

Figure 2 is a broken, sectional view, taken along the broken line II—II of Figure 1.

Figure 3 is a view partly in section and partly diagrammatic illustrating the fluid pressure system including the diaphragms for operating the press roll assembly.

As shown on the drawings:

10 The reference numeral 10 indicates generally a base for a three-roll horizontal press roll assembly embodying the features of my invention. While this invention will be described in connection with a horizontal press roll assembly such as illustrated in the drawings, it will be understood that the use of fluid pressure actuated means for controlling the pressure between the rolls of a press assembly is applicable to assemblies of two or more press rolls, arranged either horizontally or in vertical alignment.

15 The base 10 includes a central upstanding portion 11 on which is stationarily mounted an end bearing 12 for an end of a stationary roll 13. A similar base and upright standard serves to support a similar bearing at the other end of said roll 13.

20 Cooperating press rolls 14 and 15 are mounted upon opposite sides of the stationary roll 13 with their axes on approximately the same horizontal line as the axis of the stationary roll 13. Since each of said rolls 14 and 15 is similarly mounted, only one mounting will be described.

25 The mounting for roll 14 comprises a pair of upright members 16, one at each end of the roll 14, each of which is pivotally mounted at its lower end upon a pivot pin 17 supported in the base 10. The uprights 16 at their upper ends support the bearing housings 18 for the ends of the roll 14. Each of said uprights 16 is extended above said bearing housings 18 to provide a pair of arms 19. Each of said pairs of arms 19 has an indentation 20 formed in the edges 21 away from the stationary roll 13, the purpose of which indentation will later appear.

30 35 40 45 The bearing housings 12 of the roll 13 are provided with oppositely disposed extensions 22, 22 on the sides toward the rolls 14 and 15, respectively. Said extensions 22, 22 are bifurcated and provided with horizontal aligned bores for receiving fulcrum pins 23, 23. Levers 24, 24 are pivotally mounted intermediate their ends upon said fulcrum pins 23, 23, respectively. Said levers 24, 24 are provided at their upper ends with segmental spherical notches 25, 25 along the edges facing each other. Pins 26, 26 are normally re-

ceived in said notches 25, 25. Said pins 26, 26 are mounted in the side walls of cupped housings 27, 27 carried by shafts or rods 28, 28. Each of the rods 28, 28 has a smooth intermediate portion, 29, 29, and a threaded portion 30, 30. Collars 31, 31 are mounted on the intermediate portions 29, 29 for free sliding movement therealong. Said collars 31, 31 have integrally formed extensions 32, 32 that partially enclose the rods 28, 28 and that have side flanges on either side of said rods 28, 28 that are formed with pointed abutments 33, 33 for cooperation with the recesses 20, 20 in the pairs of upstanding ears 19, 19. Nuts 34, 34 are threaded upon the extended threaded ends 30, 30 of said rods 28, 28. Said nuts 34, 34 are provided with handles 35, 35 for their manual manipulation.

The rods 28, 28 thus serve as connections between the upper ends of the pivotally mounted standards 16, 16 and the upper ends of the pivotally mounted levers 24, 24. It is understood, of course, that the construction described is duplicated at both ends of the set of horizontal press rolls, 14, 13 and 15. By tightening up on the nuts 34, 34, the rolls 14 and 15 can be drawn into contact with the intermediate stationary roll 13.

The diaphragm mechanisms for controlling the amount of pressure contact between said rolls 14 and 13, and said rolls 15 and 13, will now be described.

The lower ends of the levers 24, 24 extend downwardly into housings 35, 35 that are mounted upon the standards 11, 11. Said lever lower ends carry circular plates 36, which are adapted to bear against diaphragms 37. Said diaphragms 37 are peripherally clamped within the housings 35 to provide fluid pressure chambers 38 on the opposite side of the diaphragms 37 from the lever end plates 36. Fluid conducting connections are established with the pressure chambers 38 by means of passages 39 extending through the walls of the standard 11.

As best shown in Figure 3 the diaphragms 35 are connected to a fluid pressure system that includes a main supply line 40, a three-way valve 41 in said supply line and provided with an exhaust line 42, the branch pipe lines 43, 43 and 44, 44, in which are mounted check valves 45, 45 and reducing valves 46, 46, respectively. Said branch lines 43 and 44 are connected to lines of piping 47, 47, in which are positioned pressure indicating gauges 48, 48. The ends of said piping 47, 47 are connected to the passages 39 leading to the fluid pressure chambers 38, 38.

In operation, a web of wet paper or fiber, indicated by the reference character W, is trained over the surface of the roll 14, which may be a suction roll, into the nip N between the rolls 14 and 13, around the under side of the roll 13 and upwardly into the nip N' between the rolls 13 and 15. From the roll 15, the web W may go to another press section or to a drier section. The pressure to be set up between the several rolls 14 and 13, and 15 and 13, will depend upon various factors, such as the moisture content of the web entering the horizontal press roll assembly, the weight of the sheet and the character of the stock. Ordinarily, the paper machine operator will know from previous experience the amount of pressure that should be used, and will adjust the reducing valves 46, 46 until the gauges 48, 48 show that the desired amount of pressure is being maintained.

As is obvious, the fluid pressure within the chambers 38 acts against the diaphragms 37,

which in turn press directly against the lower lever end pads 36. As the fluid pressure within the chambers 38 is increased, the diaphragms 37 are caused to flex outwardly, moving the lower lever end pads 36 in the same direction. Such movement of the lower ends of the levers 24 causes the upper ends of said levers to move toward each other and thus apply tension upon the rods 28, tending to draw the rolls 14 and 13, 10 and the rolls 15 and 13 to bear against each other with pressures corresponding with those established in the fluid pressure chambers 38. By observing the gauges 48, the operator can set up any desired amounts of pressure between the several 15 rolls and can maintain the desired amounts of pressure during the continued operation of the press roll assembly.

When it is desired to release the pressure between the several rolls of the press roll assembly, 20 the three-way valve 41 is turned to exhaust through the exhaust pipe 42, thereby shutting off the supply line 40, and the fluid pressure is released through the check valve 45 and the three-way valve 41 into the exhaust line 42. When not 25 in operation, pressure between the several rolls of the assembly may be reduced to nothing by backing off the nuts 34. Although the nuts 34 are shown as manually operable, motor operated ratchet means may be substituted for the hand 30 operated type. As shown in Figure 1, the pivots 17 are inside of vertical planes passed through the axes of press rolls 14 and 15 even when these rolls are in operative pressure relation with the middle roll 13. The press rolls therefore swing 35 outwardly, by the action of gravity, away from the middle roll whenever pressure on the diaphragms is released, or whenever the nuts 34 are backed off.

It should be noted by reference to Figure 1 that 40 the diaphragms 37 have only a slight amount of freedom of movement in either direction. The outer wall of the housing 35 limits movement in one direction, and the frame 11 acts as a stop in the other direction. By limiting the length of 45 travel, or the amount of displacement, of the diaphragm, the diaphragm may be of relatively heavy, thick, resilient material, such as a rubber composition. This in turn, permits the use of fairly high pressures, of the order of 50 lbs. per 50 sq. in., and therefore permits the use of small diameter diaphragm mechanisms.

Since the amount of relative movement between the rolls of the press assembly permitted by the slight movements of the diaphragms would not 55 be sufficient for the handling of the rolls when putting on felts and for other operations, the mechanical ratchets including the nuts 34 have been provided. Before starting a run of paper through the press roll assembly, the ratchets 60 would be pulled up until the rolls 14, 13 and 15 are approximately together and then fluid pressure on the diaphragms 37 would be relied upon to complete the bringing of the rolls together and to set up the desired amount of pressure 65 contact therebetween.

It will, of course, be understood that various 70 details of construction may be varied through a wide range without departing from the principles of this invention and it is, therefore, not the purpose to limit the patent granted hereon otherwise than necessitated by the scope of the appended claims.

I claim as my invention:

1. A paper making machine press roll assembly, comprising a middle roll, a stationary mount-

ing supporting said roll for rotation about a fixed horizontal axis, a roll on each side of said middle roll mounted for rotation about a horizontal axis, pivoted supports for said side rolls positioned to swing the axes of said side rolls into substantially horizontal alignment with the axis of said middle roll when the rolls are in operative pressure relationship, said pivoted supports having pivot points lying inside of vertical planes passing through the axes of said side rolls when said rolls are in operative pressure relationship, whereby said side rolls tend to swing outwardly from said middle roll under the action of gravity, rods arranged substantially horizontally one on each side of said middle roll and connected intermediate its ends to the corresponding upper end of one of said pivoted supports, screw mechanisms one on the outer end of each rod for shortening the effective length thereof, generally vertical levers one pivoted intermediate its ends to said intermediate roll mounting on each side of said middle roll and connected at its upper end to the inner end of the rod on the same side of said middle roll, and fluid pressure actuated diaphragm means acting through said vertical levers upon said side rolls to resist gravity action and maintain said side rolls in operative pressure relationship with said middle roll.

2. A paper making machine press roll assembly comprising a stationary roll-supporting standard, a middle roll mounted for rotation on a fixed horizontal axis on said standard, a pair of axially aligned uprights on each side of said middle roll, a press roll rotatably supported by each pair of uprights for rotation about horizontal axes, pivotal supports for each pair of uprights to swingably support the uprights for carrying the press rolls into pressure relationship on opposite sides of the middle roll and with the axes of all three rolls in substantial horizontal alignment, said

5 pivotal supports for each press roll lying closer to the middle roll than the axis of the press roll supported thereby even when the press roll is in pressure engagement with the middle roll so that each press roll tends to move laterally away from the middle roll under the action of gravity, and linkage assemblies between said uprights and said standard for holding the press rolls in pressure relation with the middle roll, said linkage assemblies including horizontal rods having threaded outer ends, take-up members threaded on said outer ends, vertical levers pivoted intermediate their ends to said standard and at their upper ends to the inner ends of said horizontal rods, and fluid pressure actuated diaphragms acting through said vertical levers to accurately control the pressure between the rolls.
